Charles T. Moore
HIS ATTORNEY

UNITED STATES PATENT OFFICE.

EDWARD FRANDSEN BEGTRUP, OF JERSEY CITY, NEW JERSEY, ASSIGNOR TO METAL & THERMIT CORPORATION, OF CHROME, NEW JERSEY, A CORPORATION OF NEW JERSEY.

MOLD FOR THERMITE WELDING AND THE LIKE.

Application filed November 2, 1923. Serial No. 672,316.

To all whom it may concern:

Be it known that I, EDWARD F. BEGTRUP, a citizen of the United States, and a resident of Jersey City, in the county of Hudson and State of New Jersey, have invented certain new and useful Improvements in Molds for Thermite Welding and the like; and I do hereby declare the following to be a full, clear, and exact description of the invention, such as will enable others skilled in the art to which it appertains to make and use the same.

The invention relates to an improvement in molds for welding the ends of railway rails and similar irregular sections by the application of superheated metal, such as would be produced by the thermite method, in which the sections to be welded and the interior of the mold are preheated by means of an oil or gas flame, directed into the mold through a heating gate, usually located near the bottom of the mold. The object of the invention is to provide means for venting the products of combustion from the portions of the mold in which said products would be entrapped and result in an uneven heating of parts of the sections and the mold and the consequent impairment of the welded joint.

30 The invention is illustrated in the accompanying drawing, in which:

The figure is a sectional elevation through a typical thermite mold for welding the adjacent ends of two railway rails.

35 Referring to the drawing, 10 indicates the mold proper which is adapted to be clamped about the ends of the rail sections in well known manner to provide a cavity 11 surrounding the rail ends and into which the superheated molten metal is charged to fuse with and weld the adjacent rail sections together in a substantial homogeneous joint. It is customary to provide molds of this character with a heating gate, such as 1, preferably located near the bottom of the mold and communicating with the lower section of the mold cavity, through which gate a preheating medium, such as a gas or oil flame, is directed for the purpose of preheating the ends of the rails or other sections to be welded and the adjacent interior walls of the mold cavity. The egress of spent gases or products of combustion from

the interior of the mold during the preheating operation has heretofore been taken care of by the usual riser opening 2, pouring gate opening 3, and vent opening 4, at the top of the mold. It has been found, however, that these openings are insufficient to provide a proper and complete evacuation of the products of combustion from those portions of the mold cavity which constitute lateral pockets or recesses, which occur at the base of the rail sections or adjacent to projections of other irregular sections, and, when the spent gases are not completely evacuated from the mold cavity, a uniform and efficient preheating cannot be effected because of the entrapped spent gases, which act as an insulating medium and prevent the hot active gases reaching the surface of the sections to be welded and the surrounding walls of the mold cavity, which are enveloped or screened by the dead gases. As a result, the preheating cannot be uniformly effected and the resultant welded joint will be correspondingly impaired. It has been discovered, however, that if the pockets or recesses, constituting portions of the mold cavity, be provided with separate vents, a complete evacuation of the products of combustion or spent gases may be readily effected and uniform heating of the sections to be welded and the interior of the mold cavity can be brought about without delay.

40 In the particular exemplification of the invention illustrated in the drawing, a vent opening 5 extending laterally from the re-entrant cavity 6 into which the base 7 of the rail projects, provides a discharge for the spent gases which would otherwise tend to accumulate in the cavity 6. Preferably the vent opening 5 is located opposite the heating gate 1, so that the spent gases will be swept out of the lower portion of the mold cavity and the hottest portions of the heating gases will be permitted to impinge directly upon the rail ends and the walls of the mold cavity.

45 While the invention has been illustrated as applied to a mold for welding the ends of railway rails, it will be understood that it will be equally applicable to all molds of this general type, which include a heating gate and which involve pockets or recesses

within the mold cavity which would tend to trap and retain the products of combustion.

What I claim is:

- 5 1. A mold for welding railway rails and the like, having a heating gate at the bottom thereof, and a vent opening substantially opposite said gate.
- 10 2. A mold for welding irregular sections, involving a pocket or recess in the mold cavity, said mold having a heating gate

connecting with the interior at the bottom thereof, and a vent opening connecting the pocket or recess with the exterior of the mold.

- 15 3. A mold for welding railway rails and the like, having a heating gate at the bottom thereof, and a vent opening adjacent the base of the mold cavity.

In testimony whereof I affix my signature.

EDWARD FRANDSEN BEGTRUP.
